Application January 10, 1938, Serial No. 184,180

17 Claims. (Cl. 95—73)

5 My invention relates generally to the art of printing and has particular reference to the art of rotary printing. Somewhat more specifically, my invention relates to transfer apparatus for exposing sensitized photogravure printing cylinders, especially cylinders of relatively large diameters, preparatory to the etching thereof.

10 The present application is a continuation in part of my co-pending application Serial No. 130,647 which was filed on March 13, 1937, and which is assigned to the assignee of the present invention.

There has long been a need in the photogravure printing art for apparatus operable to 15 photographically transfer designs or pictures directly from suitable photographic transparencies, or the like, to sensitized printing cylinders, especially cylinders of large diameters, thereby eliminating the use of the carbon tissue or similar means now employed in making rotogravure cylinders. This need has been met in part by the apparatus disclosed in my co-pending application Serial No. 130,647, but where headroom is limited the vertical apparatus may become 20 impracticable on account of the height needed to handle large diameter cylinders. Accordingly, the principal object of the present invention is to provide an improved apparatus of the subject type which can be used in conjunction with 25 large printing cylinders of varying diameters, and which will operate at high light intensities, in order to minimize the printing time. Another object of the present invention is to provide an improved light source for use in conjunction 30 with transfer apparatus of the previously described general type which may be located beneath the printing cylinder and the photographic transparency bearing the picture or design which is to be transferred thereto during the transfer 35 operation. It might be mentioned at this point that the positioning of the light source beneath the cylinder and the transparency during the transfer operation has heretofore been considered impractical, chiefly because of the inability 40 of prior art apparatus to provide for dissipation of the great amount of heat liberated by a high intensity light source.

Further objects of the invention are to provide 45 an improved means for obtaining high pressure line contact between a photographic transparency, especially one of the plate type, and the sensitized surface of a printing cylinder during transfer operations of the type contemplated herein, and generally to provide an 50 improved, easily operable transfer machine ac-

cording to the principal object of the invention. Other objects and further important advantages of the invention will be made apparent by reference to the accompanying drawings and the following description of one particularly satisfactory embodiment of the invention. Referring 5 to these drawings,

Figure 1 is a perspective view of a complete transfer machine embodying the principles of the present invention; 10

Figure 2 is a plan view, partially in section, of the transfer machine illustrated more completely in Figure 1;

Figure 3 is a fragmentary sectional view on the general line 3—3 of Figure 2; 15

Figure 4 is a sectional view on the general line 4—4 of Figure 1;

Figure 5 is a fragmentary view illustrating the automatic operation of the support means for the carrier plate for the photographic transparencies or designs which are to be transferred to the sensitized printing cylinder; 20

Figure 6 is a fragmentary view illustrating certain of the features of the improved pressure securing mechanism utilized for accomplishing 25 line contact between the transparency and the sensitized printing cylinder;

Figures 7 and 8 are fragmentary views illustrating the features of the actuating mechanism for the pressure securing means; 30

Figure 9 is a perspective view of one of the presser members forming a part of the pressure securing means;

Figure 10 is a sectional view on the general line 10—10 of Figure 9;

Figure 11 is a perspective view of the reflector and light hood used in conjunction with the apparatus of my invention; and

Figure 12 is a diagrammatic view illustrating the heat transfer means constituting a part of 40 my invention.

As illustrated particularly in Figures 1 and 2, the transfer mechanism of my invention is provided with a rigid base frame 13, rectangular in outline and preferably formed of welded, structural steel channels. A pair of upstanding, cast metal, end yokes 15 are bolted to the ends of the base frame 13 and serve to support a pair of spaced, cylindrical guides 17 in exactly parallel relation. 45

The transfer of the design or picture which it is desired to reproduce on the printing cylinder is most satisfactorily accomplished by the use of film transparencies preferably prepared in accordance with the methods disclosed in my 55

co-pending application, Serial No. 105,852. During the transfer operation these transparencies are carried upon a flat plate 19, preferably of relatively thick, plate glass, which is supported at its ends upon a pair of spaced cross heads 21. The cross heads 21 are provided with journal portions adapted to slidably engage the cylindrical guides 17 and are rigidly held in spaced relationship by a pair of channel sections 23 bolted or otherwise affixed thereto. To aid in positioning and holding the carrier plate 19, the cross head members 21 are provided with positioning slots 25 adapted to receive the ends of the glass carrier plate 19, and to minimize the danger of breaking the glass carrier plate 19 during use, suitable cushion supports 26 of rubber or the like are provided in the slots 25. Adjustable clamp members 27 having resilient bearing portions 28 (Figure 3) are provided for clamping the ends of the carrier plate 19 in place within the slots 25.

The cross head members 21 are slidable upon the guides 17, and hence together with the side channels 23 constitute a rigid support for the carrier plate 19 by means of which it becomes possible to move that later longitudinally from one end of the machine to the other in tangential contact with the cylinder during the transfer operation. Movement of the carrier plate support upon the guides 17 is accomplished by a pair of driving screws 29 supported at one end upon the lefthand yoke 15 (Figure 2) and adapted to engage suitable threaded portions in the adjacent cross head 21. The screws 29 are mechanically interconnected by means of two gears 31, one of which is keyed to the outer end of each screw, and a shaft 33 having worm gears 34 for engaging the gears 31. The shaft 33 is adapted to be driven by a variable speed motor drive mechanism 35 through a pair of right angle hand gears 36, only the uppermost of which is visible in Figure 2.

The drive mechanism 35 is illustrated particularly in Figure 2 and includes a constant speed motor 37 having a drive shaft 38 connected at one end by a belt 39 to a high speed drive pulley 40 which is supported upon, and is freely rotatable relative to, a hollow shaft or sleeve 41. The sleeve 41 is slidably keyed to the main shaft 41* which operates the driving element of the right angle gears 36. The other end of the motor drive shaft 38 engages a gear reduction mechanism 42 which is connected by a chain belt 44 to a low speed drive pulley 43, also supported upon, and freely rotatable relative to, the sleeve 41*. A friction clutch 45 is positioned at either end of the sleeve 41, and these clutches 45 are actuatable, in response to movement of a handle 46, to connect either of the drive pulleys 40 or 43 to the shaft 41* whereby that shaft and the drive screws 29 for the carrier plate support may be driven at either high or low speed.

During the transfer operation the sensitized printing cylinder, as illustrated at 47, is supported transversely of the transfer machine at substantially the mid point thereof, and as an aid to securing the proper degree of contact pressure between transparencies carried upon the carrier plate 19 and the surface of the printing cylinder, it is desirable that the cylinder support shall be vertically adjustable. The structure illustrated in the drawings is provided with such a support means, this means including a pair of hollow, cast or fabricated, uprights 49 extending between the longitudinal sections of the base frame 13

and the guide members 17. Yokes 51 adapted to engage ball bearings 50 or the like located on the ends of the printing cylinder 47 are vertically adjustably supported upon these uprights 49 by means of two pairs of cylindrical members 52 which slidably engage suitable guide passageways formed in the uprights 49. The lower ends of each pair of these members 52 are connected together by a cross head 53. A threaded lift rod 53^a engages each of the cross heads 53 at its upper end, and at its lower end engages a cam 53^b (Figure 4) formed in a shaft 54 extending transversely across the machine. It will be evident that when this shaft is rotated, as by the crank 54^a, it will be possible to raise or lower the cylinder supporting yokes 51 a sufficient distance to permit the surface of the printing cylinder 47 to be brought into tangential contact with the upper surface of the transparencies positioned upon the carrier plate 19. By the use of lift rods 53^a having threaded engagement with the supports for the printing cylinder, it is a simple matter to adjust the height of the cylinder support in order that the machine may accommodate cylinders of various diameters. A lock nut 54^b is preferably provided on each of the lift rods 53^a for maintaining the adjustment of those rods during use of the machine.

During the transfer operation, a narrow beam of light of very high intensity is directed through the plate 19 and the transparencies carried thereon along the line of tangential contact with the printing cylinder 47. At the same time, the transparency carrier plate 19 is slowly traversed from one side of the machine to the other, the rate of movement determining the duration of the exposure, and during this traversing movement the glass plate and the transparencies carried thereon are maintained in tangential contact with the cylinder. To accomplish satisfactory transfer of the design or picture formed in the transparencies it appears necessary that there be relatively high contact pressure along the line of tangency of the printing cylinder and the transparencies carried on the plate 19. This pressure incidentally produces sufficient friction between the printing cylinder and the surface of the transparencies carried on the carrier plate 19 to cause rotation of the printing cylinder at a peripheral speed exactly equal to the rate of movement of the transparency carrier plate 19 when that plate is traversed from one side of the machine to the other. It is desirable, if not in fact necessary, that ball or other low friction bearings such as the bearings 50 shall be utilized in conjunction with the support for the printing cylinder 47 in order to minimize the force required to rotate the cylinder during the transfer operation.

The means employed for securing the necessary high degree of pressure along the line of tangential contact between the printing cylinder and the transparencies carried on the plate 19 constitutes one of the most important features of the present invention, and is illustrated in some detail in Figures 3 and 6 through 10. Generally speaking, this means constitutes a pair of elongated presser members 55 adapted to be pressed against the under surface of the transparency carrier plate 19 at either side of, and very close to, the line of tangential contact between the upper surface of the transparency carrier plate 19 and the printing cylinder. The presser members 55, as is illustrated particularly in Figures 3, 6, and 9, are provided with anti-friction bearing portions 56 of hard fiber or simi-

lar material for engaging the under surface of the transparency carrier plate 19. Because of the considerable length of the presser members 55 and the heavy pressures which they must exert, those members are supported by a plurality of spaced support arms 57 adjustably attached thereto by bolts 58 or the like, as illustrated in Figures 3 and 9. These support arms 57 are pivotally supported intermediate their ends by two suitably positioned shafts 59 which extend transversely of the machine, and to prevent bending of the shafts 59, they are supported intermediate the arms 57 by bearing blocks 61 bolted or otherwise attached to rigid cross members 63, the ends of which are bolted to the central uprights 49. The outwardly projecting end of each of the support arms 57 is biased to bring the associated presser member 55 into contact with the under surface of the transparency support plate 19 by means of a compression spring 65, the reaction force of which is transmitted to the support arm through a pin 67 which extends through a suitable passageway in the transverse supports 63 for the shafts 59.

It will be apparent that through the use of the separate support arms 57 located at spaced intervals along the length of the presser members 55, it is possible to obtain very high contact pressure between the upper surface of the transparency carrier plate 19 and the surface of the cylinder in tangential contact therewith. Further, since the line of application of the force exerted by the presser members 55 is located only a short distance to either side of the line of tangential contact, the transparency carrier plate 19 is subjected to only relatively slight bending stresses during the transfer operation.

The edges of the presser members 55 are utilized to determine the width of the slot 69 through which the light passes during the transfer operation, and since the openings 70 for receiving the shanks of the bolts 58 which serve to attach the support arms 57 to the presser members 55 are elongated (see Figures 9 and 10), it is possible to readily adjust the width of this slot 69.

It is desirable that the presser members 55 shall bear against the under side of the transparency carrier plate 19 only when the printing cylinder is in tangential contact with that plate. Accordingly, the apparatus includes means for relieving the pressure exerted by the presser members 55 whenever the operator may so desire. This means, as is illustrated particularly in Figures 3, 6, and 8, constitutes a pair of elongated, transversely extending members 71 arranged for vertical movement into and out of engagement with the lower ends of the pins 67 which transmit the reaction forces of the compression springs 65 to the individual arm supports 57 for the pressure members. Suitable guides 73 and 74 determine the path of movement of the spring release members 71, and the simultaneous raising and lowering of these release members is effected by means of two mechanically interconnected, transversely extending shafts 75 which are connected to the release members 71 through suitable toggle linkages 76, the shafts 75 being actuated in response to the rotation of a crank 77 by other toggle linkages 78.

The means utilized to produce the high intensity beam of light which is directed through the transparency carrier plate 19 and the transparencies carried thereon during the exposing of

the sensitized surface of the printing cylinder 41 includes a downwardly flaring light hood 79 and a unitary reflector and lamp structure. The light hood 79 is rigidly supported upon the central uprights 49 as is illustrated in Figures 3 and 4. The bottom of the hood 79 is open, and the top is provided with a narrow slot 81 which aligns with the light slot proper 69.

The unitary reflector and lamp structure comprises a reflector unit 83, generally rectangular in outline, which serves as the frame of the structure and four automatic arc lamps 85 supported upon said reflector unit. The carbons 87 of these lamps 85 extend into the reflector unit through suitable openings 88 formed in the sides thereof, and to aid in attaining maximum illumination, the inner surface of the reflector unit 83 is formed to define four separate reflector sections 89, one for each arc.

To permit inspection of the carbons 87 and the reflector sections 89 of the reflector unit 83, the reflector and lamp structure is preferably supported by means so arranged that that structure may be readily moved from its normal position beneath the hood 79 to a position such as is indicated by the dotted lines 91 in Figure 3. In the machine illustrated in the drawings, this support means includes a pair of guide members 93 rigidly supported upon the central uprights 49. These guide members are adapted to be slidably engaged by two supporting brackets 95, one of which is affixed to either end of the reflector unit 83. Slidable movement of the structure on the guides 93 is preferably accomplished by means of two toggle linkages 97, actuated in unison by a transverse shaft 98, the shaft being operated by a suitable crank 99.

The physical construction of the automatic arc lamps 85 is not an important part of the present invention and various commercially available types may be used. To minimize printing time, however, it is very desirable that the arc lamps shall be of sufficient capacity to produce a beam of very high light intensity. The embodiment of the invention illustrated in the drawings is provided with four, 100 ampere arc lamps spaced apart about 12 inches from center and positioned so that the distance from the center of the carbons to the bottom surface of the transparency support plate 19 is about 10 inches.

It should be noted that the arc lamps and reflector assemblage and the hood 79 are normally positioned directly beneath the line of contact of the printing cylinder and the transparency carrier plate 19. This arrangement, as suggested previously, is an important feature of the present invention and constitutes a radical departure from the constructions heretofore utilized in the art.

There are numerous advantages resulting from the positioning of the arc lamps and reflector assemblage directly beneath the area of contact between the transparency carrier plate 19 and the cylinder. For example, debris from the carbons is thereby prevented from falling in the direction of the transparency supporting plate 19, and it becomes unnecessary to provide intermediate plates or the like for catching this debris; transfer machines embodying this constructional arrangement are much easier to use than the older types wherein the lamps are above or at the side of the transparency carrier. The arc lamps may be utilized at higher efficiency than in the older constructions since 75

more light is emitted from the upper side of the horizontal arc lamp than from any other side; and, generally, the cost of the apparatus is materially lessened. Yet despite these advantages, prior to the present invention it was considered highly impractical, if not in fact dangerous, to locate the arc lamps and reflector assemblage of a high intensity light source beneath the printing area, primarily due to the excessive heating which occurred at the printing area.

The apparatus of the present invention effectively accomplishes the dissipation of this heat by means of a cooling system of a very particular type. As illustrated in Figures 3 and 4, the walls of the reflector housing 83 are hollow and are provided with inlet and outlet pipes 101 and 102 whereby a cooling liquid may be continually circulated through the hollow interior thereof. Likewise, the walls of the hood 79 are also of hollow construction, and inlet and outlet pipes 103 and 104 are provided to permit cooling liquid to be circulated therethrough. Of even more importance than the hollow wall construction of the reflector 83 and the hood 79, the presser members 55 are of hollow construction and provided with inlet and outlet pipes 105 communicating with the hollow interior thereof.

During operation of the machine the several inlet and outlet pipes are connected together by conduits 107, preferably as illustrated in Figure 12, and a suitable cooling liquid is forced through the hollow interior of the presser members 55, the hood 79, and the reflector 83 in the order stated. In combination, this arrangement makes possible the location of the arc lamps and reflector assemblage beneath the transparency carrier while permitting the use of very high intensity illumination. It is not necessary, of course, to use a recirculating system for the cooling liquid; ordinary city water, for example, may be used as the cooling liquid, the water which is heated by passing through the machine being discharged into the sewer.

Since the transparency carrier plate 19 must of necessity be rather long in order to accommodate sufficient copy for a large diameter printing cylinder, it is desirable to provide means intermediate the cross heads 21 for supporting that plate as it is traversed from one end to the other of the machine during a transfer operation. One means for accomplishing this is illustrated in Figure 5 and comprises two sets of three transverse support members 109 which are connected to each other so as to be maintained in fixed relationship by suitable tie rods 111. Three of the support members 109 are located on each side of the presser members 55 and both ends 112 of each of the support members 109 are accurate and adapted to slidably engage the guide rods 17 with a bearing engagement. If desired, the upper surface of the support members 109 may be covered with a strap 113 (Figure 4) of fiber or like material to prevent scratching the under side of the transparency carrier plate 19. It will be evident that when the transparency carrier plate 19 is traversed from one side of the machine to the other the support members 109 will be moved between the two extreme positions illustrated in Figures 2 and 5, to continuously provide support for the intermediate portions of the carrier plate 19.

During normal operation of the transfer machine, photographic transparencies or the like bearing the design which it is desired to transfer to the printing cylinder will preferably be stripped onto the glass transparency carrier plate 19 by any one of the means known to the art. The plate 19 will then be placed in position upon the cross heads 21 constituting a part of the carrier plate support mechanism and will be fastened in position by tightening down the clamp members 27. The printing cylinder 47 to which a suitable sensitized coating has been previously applied will then be placed in position upon the supporting yokes 51, and with the transparency carrier plate 19 in position therebeneath, the cylinder will be lowered into light, tangential contact with the upper surface of that plate by operation of the crank 54. Then, the crank 71 will be operated to release the biasing springs 67 for the presser members 55, whereupon those members will be moved into engagement with the under side of the transparency carrier plate 19 at either side of the line of tangential contact between the cylinder and the upper surface of the carrier plate 19. The pressure exerted by the springs 67 assures even high pressure contact between the surface of the cylinder and the upper surface of the transparency carrier plate 19 during the transfer operation.

Next, motor driven mechanism 37 which actuates the drive screws 29 for the transparency carrier plate support will be energized, and simultaneously arc lamps 85 constituting the light source will be turned on. The exposing or transfer operation then proceeds automatically, the glass plate bearing the transparencies being traversed at a uniform rate of speed horizontally across the machine in tangential contact with the peripheral surface of sensitized printing cylinder 47 which rotates with a peripheral speed exactly equal to the speed of movement of the transparency supporting plate.

Suitable limit switches 115 serve to automatically stop the driving motor 37 for the drive screws 29 and to shut off the arc lamps 85 at the conclusion of the transfer operation. The lever 71 is then operated to relieve the force exerted on the under surface of the plate 19 by the biasing springs 67 for the presser members 55, following which the printing cylinder 47 may be removed from the machine, developed and etched. It is, of course, evident that cylinders which are exact duplicates of each other may be produced in this manner. Heretofore, it has been considered practically impossible to produce duplicate cylinders, especially by processes which require the use of carbon tissue, as in rotogravure.

It will be apparent that the apparatus which I have described in the foregoing is capable of accomplishing the objects of the invention in a most satisfactory manner. Through the use of cooling means of the particular described type, it is possible to employ a very high intensity light source located beneath the line of contact between the transparencies carried on the transparency carrier plate and the printing cylinder. Further, this location of the light source not only eliminates the manifold objections of light sources located above or at the side of the printing cylinder, but, in addition, renders the entire apparatus much easier and much more flexible to operate, especially by facilitating the placing of the printing cylinder in position thereon.

The apparatus of my invention includes means for securing high pressure along the printing

area without any danger of breaking the transparency carrier plate regardless of the width of such plate. Also, the device includes means for adequately supporting the transparency carrier plate throughout the transfer operation.

It will be evident that the principles which have been disclosed in the foregoing are capable of embodiment into structures of various types. Accordingly, it is my desire that the accompanying claims shall be accorded the broadest possible construction consistent with the language appearing therein and the prior art.

I claim the following as my invention:

1. In apparatus of the class described, means for supporting a printing cylinder for rotatable movement about a horizontal axis, means including a flat, relatively rigid plate member for supporting a photographic transparency for horizontal, longitudinal movement beneath and in tangential contact with said cylinder, means for longitudinally moving said transparency in tangential contact with said cylinder, means including a pair of spring actuated, elongated presser members located respectively on opposite sides of and closely adjacent to the line of tangential contact between said cylinder and said transparency for creating sufficient pressure along said line of tangential contact to cause said cylinder to be rotated when said transparency is moved longitudinally solely because of the frictional contact therebetween, and means located beneath said transparency and said cylinder for directing a relatively narrow, high intensity beam of light between said presser members and through said transparency along said line of tangential contact, the separation of said presser members determining the width of said beam.

2. In a transfer machine of the class described, the combination of a main frame, parallel guideways on said frame disposed in a horizontal plane, a frame for carrying a photographic transparency slidably mounted on said guideways, a printing cylinder rotatably mounted above and crosswise of said last named frame, means for longitudinally moving said last named frame with said transparency in tangential contact with the periphery of said cylinder, spaced hollow presser plates for creating a pressure contact between the engaging surfaces of said transparency and said cylinder, means underlying said transparency for creating and directing a relatively narrow and concentrated beam of light between said presser plates and through said transparency onto said cylinder at the area of contact therebetween, and means for circulating a cooling fluid through said presser plates.

3. In a transfer machine of the class described, the combination of a main frame, parallel guideways on said frame disposed in a horizontal plane, a frame for carrying a photographic transparency slidably mounted on said guideways, a printing cylinder rotatably mounted above and crosswise of said last named frame, means for longitudinally moving said last named frame with said transparency in tangential contact with the periphery of said cylinder, spaced hollow presser plates for creating a pressure contact between the engaging surfaces of said transparency and said cylinder, water jacketed means underlying said transparency for creating and directing a relatively narrow and concentrated beam of light between said presser plates and through said transparency onto said cylinder at the area of contact therebetween, and means for circulating a cooling fluid through

said presser plates and the jackets of said beam creating and directing means in series.

4. In a transfer machine of the class described, the combination with a rotatable printing cylinder, and means for effecting rectilinear movement of a horizontally disposed photographic transparency carrier plate in tangential contact with said cylinder, of means for pressing said carrier plate against said cylinder adjacent the line of contact comprising an elongated presser plate underlying said carrier plate, a fixed support, a group of levers pivoted intermediate their ends on said support and carrying said presser plate on one arm thereof, headed pins mounted in the other arms of said levers, and thrust springs confined between said support and the heads of said pins and through said levers forcing said presser plate against the under side of said carrier plate.

5. In a transfer machine of the class described, the combination with a rotatable printing cylinder, and means for effecting rectilinear movement of a horizontally disposed photographic transparency carrier plate in tangential contact with said cylinder, of means for pressing said carrier plate against said cylinder adjacent the line of contact comprising an elongated presser plate underlying said carrier plate, a fixed support, a group of levers pivoted intermediate their ends on said support and carrying said presser plate on one arm thereof, headed pins mounted in and depending from the other arms of said levers, thrust springs confined between said support and the heads of said pins and through said levers forcing said presser plate against the under side of said carrier plate, and means for simultaneously lifting said pins to relieve the pressure of said presser plate on said carrier plate.

6. In a transfer machine of the class described, the combination with a rotatable printing cylinder, and means for effecting rectilinear movement of a horizontally disposed photographic transparency carrier plate in tangential contact with said cylinder, of means for pressing said carrier plate against said cylinder adjacent the line of contact comprising an elongated presser plate underlying said carrier plate, a fixed support, a group of levers pivoted intermediate their ends on said support and carrying said presser plate on one arm thereof, headed pins mounted in and depending from the other arms of said levers, thrust springs confined between said support and the heads of said pins, a lifter bar underlying said pins, and means for bodily raising said lifter bar into lifting contact with said pins whereby to relieve the pressure of said presser plate on said carrier plate.

7. In apparatus of the class described, means for supporting a printing cylinder for rotatable movement about a horizontal axis, means including a flat, relatively rigid plate member for supporting a photographic transparency for horizontal, rectilinear movement beneath and in tangential contact with said cylinder, means for longitudinally moving said plate member and transparency while said transparency is in tangential contact with said cylinder, means for creating sufficient pressure along the line of tangential contact between said cylinder and said transparency to cause said cylinder to be rotated in response to longitudinal movement of said transparency and said transparency support plate solely because of the frictional contact therebetween, said last mentioned means includ-

ing at least one elongated presser member arranged to engage the under surface of said transparency support plate adjacent said line of tangential contact.

5. In apparatus of the class described, means for supporting a printing cylinder for rotatable movement about a horizontal axis, means including a flat, relatively rigid plate member for supporting a photographic transparency for horizontal, rectilinear movement beneath and in tangential contact with said cylinder, means for longitudinally moving said plate member and transparency while said transparency is in tangential contact with said cylinder, means for creating sufficient pressure along the line of tangential contact between said cylinder and said transparency to cause said cylinder to be rotated in response to longitudinal movement of said transparency and said transparency support plate solely because of the frictional contact therebetween, said last mentioned means including at least one elongated presser member supported at spaced intervals along its length and biased to engage the under surface of said transparency support plate adjacent said line of tangential contact.

9. In apparatus of the class described, means for supporting a printing cylinder for rotatable movement about a horizontal axis, means including a flat, relatively rigid plate member for supporting a photographic transparency for horizontal, rectilinear movement beneath and in tangential contact with said cylinder, means for longitudinally moving said plate member and transparency while said transparency is in tangential contact with said cylinder, means for creating sufficient pressure along the line of tangential contact between said cylinder and said transparency to cause said cylinder to be rotated in response to longitudinal movement of said transparency and said transparency support plate solely because of the frictional contact therebetween, said last mentioned means including at least one elongated presser member arranged to engage the under surface of said transparency support plate adjacent said line of tangential contact, said presser member being of hollow construction, and said apparatus including means for circulating a cooling liquid through said hollow presser member.

10. In a transfer machine of the class described, the combination of a main frame, parallel guideways on said frame disposed in a horizontal plane, a flat, relatively rigid plate for supporting a photographic transparency, a frame supporting said transparency support plate for slidable movement on said guideways, a freely rotatable printing cylinder mounted above said transparency support plate crosswise of the direction of movement thereof, the peripheral surface of said cylinder being in tangential contact with the transparency supported upon said transparency support plate, means for moving said supporting frame and said transparency support plate along said guideways during the operation of said machine, and means for producing sufficient pressure between the transparency supported upon said transparency support plate and said cylinder along said line of tangential contact to cause said cylinder to be rotated at a peripheral speed equal to the speed of longitudinal movement of said transparency carried plate solely because of the resultant friction.

75. 11. In a transfer machine of the class de-

scribed, the combination of a main frame, parallel guideways on said frame disposed in a horizontal plane, a flat, relatively rigid plate for supporting a photographic transparency, a frame supporting said transparency support plate for slidable movement on said guideways, a freely rotatable printing cylinder mounted above said transparency support plate crosswise of the direction of movement thereof, the peripheral surface of said cylinder being in tangential contact with the transparency supported upon said transparency support plate, means for moving said supporting frame and said transparency support plate along said guideways during the operation of said machine, means for producing sufficient pressure between the transparency supported upon said transparency support plate and said cylinder along said line of tangential contact to cause said cylinder to be rotated at a peripheral speed equal to the speed of longitudinal movement of said transparency carrier plate solely because of the frictional engagement between said transparency carrier plate and said printing cylinder, said last mentioned means comprising at least one elongated presser member supported at spaced intervals along its length and biased to engage the under surface of said transparency support plate adjacent said line of tangential contact.

12. In apparatus of the class described, a printing cylinder, means for supporting said cylinder for rotatable movement about a horizontal axis, means including a flat, relatively rigid plate member for supporting a photographic transparency for horizontal, rectilinear movement beneath and in tangential contact with said cylinder, means for longitudinally moving said plate member and transparency while said transparency is in tangential contact with said cylinder, means for producing sufficient pressure along the line of tangential contact between said cylinder and said transparency to cause said cylinder to be rotated in response to longitudinal movement of said transparency and said transparency support plate, means located beneath said transparency support plate and said cylinder for directing a narrow, high intensity beam of light through said transparency support plate and said transparency along said line of tangential contact, and means for preventing excessive heating of said transparency along said line of tangential contact including at least one hollow, elongated member which slidably engages the under surface of said transparency support plate adjacent said line of tangential contact, and means for circulating cooling fluid through said hollow member.

13. In a transfer machine of the class described, the combination of a main frame, parallel guideways on said frame disposed in a horizontal plane, a flat, relatively rigid plate for supporting a photographic transparency, a frame for supporting said transparency support plate for slidable movement on said guideways, a printing cylinder rotatably mounted above said transparency support plate crosswise of the direction of movement thereof, the peripheral surface of said cylinder being in tangential contact with the transparency supported upon said transparency support plate, means for longitudinally moving said supporting frame and said transparency support plate during the operation of said machine, means including at least one elongated, hollow presser member adapted to bear against the under surface of said trans-

parency carrier plate to produce sufficient pressure between the transparency supported upon said transparency support plate and said cylinder to cause said cylinder to be rotated in response to movement of said transparency and said transparency support plate, means located beneath said transparency support plate and said cylinder for directing a narrow, high intensity beam of light through said transparency support plate and said transparency along said line of tangential contact, and means for circulating cooling fluid through said presser member.

14. In a transfer machine of the class described, a main frame, means including a flat, relatively rigid plate member for supporting a photographic transparency for horizontal, rectilinear movement on said main frame, a printing cylinder disposed above and crosswise of the direction of movement of said transparency support plate, bearings for the end pintles of said cylinder, a vertically adjustable support member for each of said bearings mounted on said main frame, and means for simultaneously raising and lowering said bearing support members and said bearings predetermined equal amounts, said last mentioned means comprising a rock shaft journaled in, and crosswise of, said main frame and duplicate cams integrally attached to said rock shaft and arranged to operate with said vertically adjustable support members to effect the simultaneous raising or lowering of said bearing support members in response to rotation of said rock shaft.

15. In a transfer machine of the class described, the combination of a main frame, parallel guideways on said frame disposed in a horizontal plane, a flat, relatively rigid transparency support plate, a secondary frame supporting said transparency support plate for slidable movement on said guideways, means for traversing said secondary frame and said transparency support plate from one end of said machine to the other, and automatic means for supporting said plate at spaced intervals therealong during said traversing operation, said last mentioned means comprising a plurality of elongated support members which are arranged crosswise of the direction of movement of said transparency carrier plate and which are moved to supporting positions in response to movement of said secondary frame, each end of each of said support members slidably engaging one of said guide members, said support members being arranged in two sets, one of which is located on either side of the longitudinal center of the path of travel of said transparency support plate, and corresponding members of each set being mechanically connected to each other so as to be maintained in fixed, spaced relationship whereby when said secondary frame and said transparency support plate is moved from one end of said machine to the other the support members of one set will

be moved in the direction of said center of movement in sequence, while the corresponding support members of the other set will be moved away from said center of movement so as to progressively support the carrier plate as it is traversed from one end of said machine to the other.

16. In apparatus of the class described, a printing cylinder, means for supporting said cylinder for rotatable movement about its longitudinal axis, a photographic transparency, means including a flat, relatively rigid plate member for supporting said transparency for rectilinear movement while in tangential contact with the surface of said cylinder, means for longitudinally moving said plate member and said transparency while said transparency is in tangential contact with said cylinder, means for directing a relatively narrow, concentrated beam of light through said transparency and onto said cylinder along the line of tangential contact therebetween, means for securing an intimate pressure engagement between said cylinder and said transparency along said line of tangential contact, said last mentioned means including two elongated, hollow presser members each of which is resiliently biased into engagement with said transparency support plate adjacent said line of tangential contact, and means for circulating a cooling fluid through said hollow presser members.

17. In apparatus of the class described, a printing cylinder, means for supporting said cylinder for rotatable movement about its longitudinal axis, a photographic transparency, means including a flat, relatively rigid plate member for supporting said transparency for rectilinear movement while in tangential contact with the surface of said cylinder, means for longitudinally moving said plate member and said transparency while said transparency is in tangential contact with said cylinder, means for directing a relatively narrow, concentrated beam of light through said transparency and onto said cylinder along the line of tangential contact therebetween, means for securing an intimate pressure engagement between said cylinder and said transparency along said line of tangential contact, said last mentioned means including two elongated, hollow presser members each of which is arranged to bear against said transparency support plate at one side of and adjacent to said line of tangential contact, a stationary frame, and a plurality of spring-pressed support arms mechanically connected at one end to said frame and at the other end to said presser members at spaced intervals along the length thereof for supporting said presser members and for biasing said presser members into engagement with said transparency support plate, and means for circulating a cooling fluid through said hollow presser members.

CHARLES L. HENDERSON.
